F. OLIVER

LAMB CARRIER

Filed April 17, 1926

Inventor
Frank Oliver

By Clarence O'Brien

Attorney

UNITED STATES PATENT OFFICE.

FRANK OLIVER, OF JOHN DAY, OREGON.

LAMB CARRIER.

Application filed April 17, 1926. Serial No. 102,711.

My present invention has to do with the handling of new born lambs.

A new born lamb is ordinarily wet and slimy, and disagreeable to take hold of by hand, and moreover if a lamb is grabbed by one leg when it is new born and tender is frequently gives rise to lameness. Moreover a new born lamb cannot be properly handled by hand in such manner that the mother sheep will follow the carried lamb.

With the foregoing in mind, my invention contemplates the provision of a carrier through the medium of which the lamb may be picked up when it is lying down or 15 when it is in any other position, and the lamb may be conveniently carried and in a manner comfortable to the lamb and without liability of subjecting it to any injury, and the lamb may be conveniently carried 20 by an operative at a point adjacent to the ground where the mother sheep can conveniently smell the lamb so that the mother sheep following the lamb will be assured.

My invention also contemplates the provision of a lamb carrier so characterized that 25 it is susceptible of being readily engaged with a lamb, and this in such a manner that when raised from the ground the lamb is well balanced and may be carried with facility; it being understood in this connection that when a lamb is dropped it is desirable to carry the lamb from what is known as the drop band to a lambing shed, the lamb being carried and the mother sheep 35 following.

A further object of my invention is the provision of a lamb carrier of such type that it is adapted to be used to advantage as a neck hook in catching and holding sheep in a lambing shed or in any other place.

To the attainment of the foregoing, my invention consists in the improvement as hereinafter described and definitely claimed.

In the accompanying drawings, forming part of this specification:—

Figure 1 is a view showing a lamb by dotted lines and also showing in full lines my novel lamb carrier as properly arranged 50 for the raising of the lamb and for the convenient carrying of the lamb.

Figure 2 is a view illustrative of the mode of using my novel device as a neck hook.

Figure 3 is a broken side elevation, partly 55 in section, of my novel carrier.

Figure 4 is an elevation of the carrier

taken at right angles to Figure 3 and from a viewpoint at the left of Figure 3.

Similar numerals of reference designate corresponding parts in all of the views of 60 the drawings.

My novel lamb carrier comprises a handle 1 and a portion 2 of general hook-shape. The handle 1 is preferably of wood and about three feet in length, and the hook-shaped portion 2 is preferably formed of wire of suitable caliber and character. In the preferred embodiment of my invention the hook-shaped portion 2 includes terminals 3 designed to form a shank. The said 65 terminals 3 are socketed in the end of the handle 1 that is reinforced by a ferrule 4, and the said terminal portions or shank portions 3 are merged into oppositely directed heel portions 5 which are disposed in the 70 same vertical plane as the handle 1. At their outer ends the portions 5 are merged into the side portions 6 of the hook, the said side portions 6 being curved substantially as 75 shown and being merged in turn into a bill 80 portion 7 with a forwardly directed loop 8 of flared type at its middle.

Through the medium of the handle 1, the hook-shaped portion of my novel carrier is adapted to be positioned under the belly portion 85 of a lamb and between the fore legs and the back legs, and this without the necessity of the operative stooping to any material extent. When the hook-shaped portion of the carrier is positioned as indicated relative to 90 a lamb, and the carrier is lifted through the medium of the handle 1, which is alined with and extends upwardly from one end wall of the hook shaped portion 2, the lamb will be raised and may then be conveniently 95 carried at a point adjacent to the ground where the mother sheep can smell it so that the mother sheep will follow the lamb to the lambing shed, and when the latter point is reached, the lamb may be deposited on the 100 ground and the carrier disengaged so that the transfer of the lamb to the lambing shed will not be attended by any disagreeable features or by any injury whatsoever to the lamb.

As made clear by Figure 2 of the drawings, my novel device is also adapted to be used to advantage as a neck hook for enabling a stock man to conveniently catch and hold grown sheep and this without injuring 110 the sheep.

It will be appreciated from the foregoing

that notwithstanding the important purpose that my novel lamb carrier is adapted to serve, the carrier is simple and inexpensive in construction and is adapted to last for an indefinite period.

While I prefer to employ the precise construction herein illustrated and described, I do not desire to be understood as limiting myself to the said precise construction, my invention being defined by my appended claim within the scope of which modifications may be made without departure from my invention.

Having described my invention, what I claim and desire to secure by Letters Patent, is:—

A lamb carrier comprising a handle adapt-

ed to be carried in upright position, and a hook-shaped portion at the lower end and substantially at one side of the said handle, the said hook-shaped portion having pendent heel parts alined with and resting in the same vertical plane as the handle and extending in opposite directions from the lower end thereof, and also having dished side parts extending downwardly and laterally and upwardly from the outer ends of the heel parts and further having a bill joining the forward ends of the side parts; the said bill being provided at its middle with a flared curvilinear and forwardly extending loop.

In testimony whereof I affix my signature.

FRANK OLIVER.
